FLUORESCENT LUMINAIRE

George J. Picha, Cleveland, Ohio, assignor to Westinghouse Electric Corporation, Pittsburgh, Pa., a corporation of Pennsylvania
Continuation of application Ser. No. 364,968, May 5, 1964. This application June 16, 1966, Ser. No. 560,944
17 Claims. (Cl. 240—9)

ABSTRACT OF THE DISCLOSURE

A luminaire is particularly adapted for use in conjunction with depending beam ceilings so that the cavity formed by the depending beam construction serves as a luminaire housing. The luminaire includes an adjustable hanger from which a light diffuser or light refractor depends. The light diffuser can be readily raised or lowered with respect to the ceiling.

This application is a continuation of copending application Ser. No. 364,968, filed May 5, 1964, now abandoned by the present inventor and assigned to the present assignee.

This invention relates generally to luminaires and, more particularly, to luminaires for use with ceiling structures employing depending beams.

With the advent of pre-cast ceiling structures of the depending beam type construction, there has developed a demand, in the art of space conditioning, for lighting and lighting-air, conditioning fixtures which are tailor-made to fit the cavities formed by the depending beams and enhance the aesthetic appearance of the ceiling. Standard fixtures of the prior art have proven unsatisfactory in their adaptability to ceiling structures of this nature. In addition, with a fixture recessed into a ceiling cavity, the problem of access to the fixture through the side thereof became aggravated and in some installations very difficult to accomplish. Also because of the many different sizes of ceiling cavities, it is necessary to provide a fixture which can be adapted to provide a tailor-made appearance when mounted in ceiling cavities of varying shapes and sizes. To overcome these disadvantages in the art and still maintain an economic production cost for the fixture there has developed a need for a new and unique combination air-conditioning and illuminating fixture for use in ceiling cavities.

It is a general object of this invention to provide a luminaire for use with ceiling cavities.

A further object of this invention is to provide a luminaire which, when mounted within a ceiling cavity formed by depending beams, will present a pleasing aesthetic appearance.

Another object of the invention is to provide a combination luminaire-air-conditioning fixture which, when mounted in a ceiling cavity, will present a pleasing aesthetic appearance.

Still another object of the present invention is to provide a combination luminaire-air-conditioning fixture which is adapted to be mounted within ceiling cavities of various shapes and sizes.

Yet another object of the present invention is to provide a space-conditioning fixture which is adjustable in elevation relative to a ceiling.

A further object of the present invention is to provide a luminaire which has a floating-in-air appearance.

Still another object of the present invention is to provide a luminaire for mounting in a cavity provided by a depending beam structure wherein the depending beam comprises a part of the luminaire.

2

The aforesaid objects and other objects which will become apparent as the description proceeds are achieved by providing an inverted channel which may be mounted with its bight portion flush against the main ceiling portion within a cavity. Releasably attached to the ends of this channel are structural members which support lamp holding means and vertical hanger members for supporting the closure assembly. The closure assembly is light-transmitting. The hangers are telescopically adjustable, whereby leveling or adjusting of the closure relative to the ceiling may be achieved very simply.

For a better understanding of the nature of the invention, reference should be had to the following detailed description taken in conjunction with the accompanying drawings, in which:

FIG. 1 is a perspective view of a ceiling of depending beam construction, which is provided with several of the luminaires provided according to this invention;

FIG. 2 is a perspective view of a ceiling having depending beam construction, which is provided with combination lighting-air-conditioning fixtures provided according to this invention;

FIG. 3 is a perspective view of a ceiling employing a different type of depending beam construction, and which is provided with several of the luminaires provided according to this invention;

FIG. 4 is a perspective view, partly in section, of a luminaire provided by this invention mounted in a ceiling cavity;

FIG. 5 is another perspective view, partly broken away, of a luminaire provided by this invention, showing construction details of the luminaire;

FIG. 6 is an end view, partly in section, of a luminaire mounted in a ceiling cavity;

FIG. 7 is a side elevational view of two luminaires, mounted end to end, with one partly cut away;

FIG. 8 is a top plan view of two luminaires, mounted end to end;

FIG. 9 is a fragmentary side elevational view of the jointure between two luminaires mounted end to end;

FIG. 10 is a fragmentary end elevation view, partly in section, of a ceiling cavity having a luminaire air-conditioning duct and air diffuser mounted therein;

FIG. 11 is a side elevational view of the jointure between two luminaires, end to end, showing an air-conditioning duct and air diffuser equipped therein;

FIG. 12 is a top plan view of the jointure between two luminaires, end to end, showing the general arrangement of the air-conditioning diffuser;

FIG. 13 is an end elevational view of a modified form of a luminaire as provided by this invention, illustrating the closure assembly both in closed and open position;

FIG. 14 is a perspective view of an end of the luminaire showing a detachable lamp holder support;

FIG. 15 is a fragmentary plan view, partly in section, showing the hinge and latch mounted to the closure;

FIG. 16 is a sectional end elevational view of the closure assembly showing the hinge and latch mounted thereto, as taken along lines XVI—XVI in FIG. 15; and

FIG. 17 is a partial side elevational view showing the latch mounted to the closure.

Throughout the description which follows, like reference characters refer to like parts on the various figures.

Referring to the forms of the invention illustrated in the drawings, it can be seen that the luminaire, when mounted in a ceiling having depending beam construction, provides a pleasing aesthetic appearance. FIG. 1 illustrates a room having substantially vertical side walls 30 and 32 and a ceiling. The ceiling comprises parallel beams 34 which depend therefrom. Several luminaires

36 are mounted between the depending beams 34 and parallel thereto in tandem fashion.

FIG. 2 shows the luminaire 36 and ceiling of FIG. 1, but with the addition of an air conditioning diffuser 38 positioned between adjacent ends of two abutting luminaires.

FIG. 3 shows a ceiling having not only parallel beams 34 but also transverse beams 40 perpendicular thereto, presenting a plurality of four-sided cavities, which as shown, are equipped with luminaires 36.

As shown in FIG. 4, the main ceiling structure 42 and the depending beam structure 34 define a cavity. Components of the luminaire 36 preferably are mounted in the cavity, rendering only the light transmitting closure assembly 44 visible from the room space. The light transmitting closure assembly may include a light transmitting member of glass or some suitable plastic material. The main ceiling 42 and sides 46 and 48 of the beams 34 actually serve as the sides or housing of the luminaire 36. The sides 46 and 48 of the beams 34 may be coated with a light reflective material to assist in directing light through the light transmitting closure member 44.

FIGS. 5 and 6 clearly show the construction details of the luminaire 36. An elongated U-shaped channel member 50 having a bight or top wall portion 52 and side walls 54, provides the main support for hanging the luminaire 36 from the main ceiling 42. The channel member 50 is affixed to the main ceiling structure 42 by any suitable means such as bolts (not shown). Mounted within the channel member 50 are the electrical components 56 for the luminaire 36. Recessed grooves 58 are provided at the side walls of the channel to add rigidity. A cover member 60 is removably attached to the channel 50 by a screw 62 or any other suitable means. Longitudinally extending grooves 64 are provided in this cover member to afford a dual function. Not only do the grooves 64 add rigidity to the cover member, but also, being adjacent the turned-in portions 66 of the side walls of the channel, they prevent inward squeezing of these side walls. As will be explained subsequently, inward squeezing of the side walls effectuates removal of a lampholder support member which is attached to each end of the U-shaped channel member 50.

A downward depending end member 68 is attached to each end of the channel member 52. The end members 68 are attached to channel member 52 by welding, by tab and slot, or any other suitable means. Supported between the end members 68 and mounted thereto are reflectors 70. The reflectors 70, preferably, are composed of metal, polished on their lower surface. Conventional lampholders 72, for supporting elongated light source means such as fluorescent lamps 74 are mounted to the end members 68 adjacent the reflectors by any suitable means.

Located at the ends of the end members 68 are sleeves 76 formed integrally therewith or fastened thereto. These sleeves 76 are provided with vertical slots 78. It is to be understood that sleeves 76 of this or a similar nature may be provided other than at the end points of the end members 68. Adjustable arms 80 are located in the sleeves 76 for vertical adjustment relative to the sleeves 76. A screw 82 inserted through slot means 78 is used to secure the position of adjustable arms 80 with respect to sleeve means 76. Adjustable arms 80 provide the necessary adjustment of adjusting the elevation and for leveling closure assembly 44 which is attached to the adjustable arms 80 by means of hinges and latches which will be discussed subsequently. Alternately, the adjustable arms 80 may be mounted elsewhere on the structural members. As shown in FIG. 6, the closure member or means 44 is supported and suspended solely from the hanger arms or means 80 and all portions of the closure member 44 are spaced from the beam sides 46 and 48.

FIGS. 7, 8 and 9 show details of adjacent luminaires 36 mounted end to end. It can be seen that there is no appre-

ciable gap between the luminaires 36, rendering the appearance one of substantially continuous illumination.

Shown in FIGS. 10, 11 and 12 is another embodiment of the luminaire. Basically, it is identical to the aforementioned embodiment with the addition, however, of means for providing air-conditioning for the space illuminated. There is shown two adjacent luminaires 36 which are provided, at their junction, with an air-conditioning duct 90 and a diffuser 38. The closure assemblies 44 are designated to receive diffusers 38 and are shaped accordingly. Attachment of the diffuser rim to the closure is by clamps 94 and screws 96 or any other suitable means. The diffuser 38 conventionally is made of metal. However, a translucent material would suffice. The duct 90 is connectable to a branch air transporting duct. Sufficient flexibility exists in the duct and in the connections between duct 90, diffuser 38 and closure 44 to permit leveling adjustments of the closure 44. The duct 90 is not visible from the room beneath the closure assembly.

FIG. 13 illustrates further, the versatility of the present luminaire. In this embodiment, lampholders 72 are adapted to support three, rather than two elongated light sources 74. Accordingly, three reflectors 70 are provided. This view shows also the adjustability of the level of closure member 44, with the closure member 44 shown alternately in the closed position and the full open position.

FIG. 14 shows in detail, the structure employed for providing the lampholder support 84 and channel 52 with means for easily attaching and detaching a lampholder support 84 to the channel 52 at each end of the channel 52.

The channel 52 is provided at each end with a pair of notches 100 and 102 and a pair of tabs 104 and 106. The ends of the channel 52 are also provided with notches 108 and 110. It is also seen that a tab 112 and 114 is turned substantially at right angles to each of the side walls of the channel 52.

The lampholder support 84 comprises a substantially U-shaped member having flanges 120 and 122 turned substantially at right angles to the sides 124 and 126 of the U-shaped member. The side 124 of the U-shaped member has a pair of notches 128 and 130 therein. Each of the notches 128 and 130 is defined by a cam portion 132, a substantially horizontal portion 134 and a substantially vertical portion 136.

To assemble the lampholder support 84 to the channel 52, the notches 128 and 130 of the lampholder support 84 are lined up or mated with the tabs 104 and 106 on the channel 52 and the lampholder support 84 is moved upward. This upward movement of the lampholder support 84 will cause the tabs 104 and 106 to slide along the cam portions 132 of the slots 128 and 130 in the side 124 of the lampholder support 84. As the lampholder support 84 is moved further upward the tabs 104 and 106 will finally snap under the substantially horizontal portions 134 of the slots 128 and 130 in the side 124 of the lampholder support 84. In this position of the lampholder support 84, the notches 108 and 110 in the side walls of the channel 52 and the turned in portions 112 and 114 of the side walls of the channel 52 rest firmly on the lampholder support 84. The lampholder support 84 is in this manner firmly attached to the channel member 52.

To detach the lampholder support 84 from the channel member 52 for service, or other purposes, it merely requires that the tabs 104 and 106 be squeezed toward each other until they clear the substantially horizontal portions 134 of the slots 128 and 130. The lampholder support 84 may then be detached from the channel 52. Accidental squeezing of the tabs 104 and 106 to cause detaching of the lampholder 84 from the channel 52 is prevented by the grooves 64 which are clearly illustrated in FIG. 13. In order to remove the lampholder support 84 from the channel 52 sufficient pressure must be applied to the tabs 104 and 106 to cause the tabs to ride over the inclined outer surfaces of the grooves 64. The grooves 64 are of sufficient depth to prevent the tabs from

accidentally riding up on the inclined outer surface of the grooves 64. It is understood that a lampholder support 84 is attached in a like manner to both ends of the channel member 52.

FIGS. 15, 16 and 17 illustrate details for the closure assembly 44, hinge and latch mechanism. The closure 44 pivots about hinge pins 140 which are attached to the closure assembly 44. The hinge pins 140 rests on a bearing portion 142 provided on members 144 which are attached to the adjusting arms 80. The hinge pins 140 may be molded integrally with closure 44 or fastened thereto by any other suitable means. It is further to be understood that bearing portions 142 may be provided on the member 144 on both sides of the luminaire 36 so that the closure assembly 44 may be reversed. Likewise, a latching member 148 may be attached to the closure assembly 44 for latching the closure assembly 44 in closed position. The latching member 148 engages one of the members 144 to hold the closure assembly 44 in closed position.

It can be seen therefore that by manufacturing a standard channel, ballast and cover assembly of the type herein described, a luminaire can be installed in a ceiling cavity of various dimensions. By providing the proper size light transmitting closure assembly, structural member and lampholder support, which are all readily attachable, a versatile structure is provided which utilizes the ceiling and sides of the depending beams to comprise part of the luminaire.

Cleaning the inside of the assembly is accomplished simply by unlatching the closure assembly and dropping it down to a vertical position. If further maintenance is required, the closure assembly may easily be removed from its supporting structure. In addition replacement of electrical components is facilitated because of the suspension-type installation thereof.

From the foregoing description, it is apparent that the objects of the invention have been achieved by providing a luminaire which may be mounted within a ceiling cavity formed by depending beams with the depending beams comprising a part of the luminaire. Manufacture of the fixture is simple. The luminaire is equipped to receive air conditioning dispensing means. It has versatility in that it can be adapted to fit various size cavities. It also possesses easy access features and adjustability.

Since numerous changes may be made in the above described construction and different embodiments of the invention may be made without departing from the spirit and scope thereof, it is intended that all subject matter contained in the foregoing description or shown in the accompanying drawings shall be considered as illustrative and not in a limiting sense.

I claim as my invention:

1. The combination luminaire which comprises:

(a) luminaire housing means comprising a top wall portion and side wall portions depending therefrom;

(b) supporting means positioned within and affixed to said housing means;

(c) lampholders supported within said housing means by said supporting means and adapted to support elongated light sources within said housing means;

(d) hanger means affixed to said supporting means and extending downwardly therefrom within said housing means; and

(e) at least one light-transmitting closure means supported and suspended solely from said hanger means and positioned within said housing means, all portions of said closure means spaced inwardly from said depending side wall portions, and said closure means being readily movable to permit access to the interior of said housing means.

2. The combination as specified in claim 1, wherein said luminaire housing means is formed by part of a ceiling, said top wall portion of said housing means comprises an upper portion of said ceiling, and said side wall

portions of said housing comprise ceiling-beam portions of said ceiling which depend from said upper portion of said ceiling.

3. The combination as specified in claim 2, wherein said supporting means is affixed to said upper ceiling portion and is rendered substantially unobservable by said at least one closure means when viewed from below.

4. The combination as specified in claim 3, wherein said at least one closure means is positioned within said housing means above the lower extremities of said depending ceiling-beam portions.

5. The combination as specified in claim 4, wherein said hanger means is adjustable to different lengths to permit leveling of said at least one closure means.

6. A luminaire adapted for use in a ceiling structure having depending beams defining cavities therebetween, said luminaire comprising:

(a) an elongated, inverted, generally U-shaped channel member having a bight portion and downwardly extending side wall portions defining a bottom opening and end openings, the ends of said side wall portions provided with slotted means for engaging lampholder support means;

(b) elongated cover means attached to said channel and enclosing said bottom openings, said cover means provided with inverted, elongated, upwardly projecting V-shaped groove adjacent said side wall portions, said grooves preventing inward squeezing of said side wall portions;

(c) U-shaped lampholder support means having side wall portions provided with notches, said notches interfitting with said slotted means said support means releasable from said channel member by a slight inward squeezing of said channel side wall portions after said cover means is removed from said channel member;

(d) at least one lampholder secured to each said support means, said lampholders adapted to support elongated light source means;

(e) structural means, affixed to opposite ends of said channel and extending laterally of said channel;

(f) adjustable means depending from said structural means; and

(g) light transmitting closure means attached to said adjustable means and suspended therefrom.

7. A luminaire adapted for use in a ceiling structure having depending beams defining cavities therebetween, said luminaire comprising:

(a) an elongated, inverted, generally U-shaped channel member having a bight portion and downwardly extending side wall portions defining a bottom opening and end openings, the ends of said side wall portions provided with slotted means adapted to engage lampholder support means of various dimensions, and said channel member also adapted to support structural means of various dimensions;

(b) elongated cover means enclosing said bottom opening, said cover means provided with inverted, elongated, upwardly projecting V-shaped grooves adjacent said side wall portions, said grooves preventing inward squeezing of said side wall portions;

(c) U-shaped lampholder support means having side walls provided with notches, said notches interfitting with said slotted means, said support means releasable from said channel member by a slight inward squeezing of said channel side wall portions when said cover means is removed from said channel member;

(d) at least one lampholder secured to each said support means, said lampholders adapted to support elongated light sources;

(e) structural means affixed to opposite ends of said channel and extending laterally of said channel;

- (f) adjustable means attached to and depending from said structural means, said adjustable means adapted to assume any of a plurality of lengths;
- (g) light transmitting closure means attached to said adjustable means, said closure means being of a size to substantially enclose said cavity and render unobservable other portions of said luminaire.

8. A luminaire adapted for use in a ceiling structure having depending beams defining cavities therebetween, said luminaire comprising:

- (a) an elongated, inverted, generally U-shaped channel member having a bight portion of downwardly extending side wall portions defining a bottom opening and end openings, the ends of said side wall portions provided with mating means for engaging lampholder support means;
- (b) elongated cover means enclosing said bottom openings, said cover means provided with inverted, elongated, upwardly projecting V-shaped grooves adjacent said side wall portions, said grooves preventing inward squeezing of said side wall portions;
- (c) U-shaped lampholder support means having side walls provided with notches, said notches interfitting with said mating means, said support means releasable from said channel member by a slight inward squeezing of said channel side wall portions when said cover means is removed from said channel, and said channel means serving as a raceway for wiring between electrical components of said luminaire;
- (d) at least one lampholder secured to each said support means, said lampholders adapted to support elongated light source means;
- (e) structural means affixed to opposite ends of said channel and extending laterally of said channel;
- (f) adjustable means depending from said structural means; and
- (g) light transmitting closure means releasably hinged and latched to said adjustable means.

9. A luminaire adapted for use in a ceiling structure having depending beams defining cavities therebetween, said luminaire comprising:

- (a) an elongated, inverted, generally U-shaped channel member having a bight portion and downwardly extending side wall portions defining a bottom opening and end openings, the ends of said side wall portions provided with mating means for engaging lampholder support means, and said channel member adapted to support structural means of various dimensions;
- (b) elongated cover means enclosing said bottom opening, said cover means provided with inverted elongated, upwardly projecting V-shaped grooves adjacent said side wall portions, said grooves preventing inward squeezing of said side wall portions;
- (c) U-shaped lampholder support means having side wall portions provided with notches, said notches interfitting with said mating means, said support means releasable from said channel member by a slight inward squeezing of said channel side wall portions;
- (d) adjusting means supported by said lampholder support means; and
- (e) closure means releasably hinged to said adjusting means, said adjusting means adapted to permit leveling of said closure means, and said closure means being of size to substantially cover said cavities and render unobservable other portions of said luminaire.

10. A luminaire adapted for use in a ceiling having portions which depend from the main ceiling structure, with luminaire-retaining cavities defined by said depending portions and said main ceiling structure, said luminaire comprising:

- (a) an elongated, inverted, generally U-shaped channel member having a bottom opening and adapted to be affixed at its upper side to said main ceiling structure intermediate a pair of said depending portions;

- (b) cover means enclosing said bottom opening;
- (c) lampholder support means attached to opposite ends of said channel member;
- (d) at least one lampholder secured to each said lampholder support means and adapted to support elongated light source means;
- (e) structural means affixed to opposite ends of said channel member proximate said lampholder support means and extending laterally of said channel member;
- (f) adjustable means depending from said structural means and adapted to assume a plurality of different lengths; and
- (g) light transmitting closure means attached to said adjustable means and suspended therefrom, said light transmitting closure means being readily movable to permit replacement of said light sources.

11. The luminaire as specified in claim 10, wherein said lampholder support means comprises a raceway for wiring between electrical components of said luminaire, and said light transmitting closure means is releasably hinged and latched to said adjustable means.

12. A luminaire in combination with a ceiling, said ceiling having a main portion and portions depending downwardly therefrom, the surfaces of said main ceiling portion and said ceiling depending portions forming a plurality of housings adapted to receive luminaires, said luminaire mounted within one of said ceiling-formed housings, said luminaire comprising:

- (a) an elongated inverted channel member affixed to said main ceiling portion between an adjacent pair of said ceiling depending portions;
- (b) support members attached to said channel member proximate opposite ends thereof and extending within said one ceiling-formed housing transversely of said channel member;
- (c) at least one lampholding means secured to each said support members and adapted to support elongated light source means within said one ceiling-formed housing;
- (d) hanger means affixed to and depending from said support member, said hanger means adjustable to different lengths; and
- (e) a light transmitting closure member suspended by said hanger means and positioned generally parallel to said main ceiling portion and generally within said one ceiling-formed housing and extending between a substantial portion of the space between said adjacent pair of said ceiling depending portions, and said light transmitting closure member readily movable to permit access to the light source means.

13. The luminaire as specified in claim 12, wherein said ceiling depending portions are disposed in parallel relationship, and said elongated inverted channel member is adapted to be disposed parallel therewith.

14. The luminaire as specified in claim 12, wherein a cover member is disposed over the open bottom of said elongated inverted channel member.

15. The luminaire as specified in claim 12, wherein an air duct means is provided within said ceiling housing, and an air diffuser means is connected to said duct means and opens into the space to be illuminated by said luminaire.

16. The luminaire as specified in claim 12, wherein the surfaces of said ceiling are at least partially coated with a light reflective material to assist in directing light through said light transmitting member.

17. A plurality of luminaires in combination with a ceiling formed by portions depending from a main upper portion, the surfaces of said depending portion and said upper portion forming a plurality of housings for said plurality of luminaires, at least two of said luminaires mounted in end-to-end abutting relationship within one of said ceiling-formed housings, said luminaires each comprising:

- (a) an elongated channel member affixed to said main ceiling portion between and generally parallel to an adjacent pair of said ceiling depending portions;
- (b) at least two support members attached to said channel member and extending within said one ceiling-formed housing transversely of said channel member and said depending portions; 5
- (c) at least one lampholding means secured to each said support member and adapted to support elongated light source means within said one ceiling-formed housing;
- (d) hanger means affixed to and extending from said support members;
- (e) a light transmitting member movably suspended by said hanger means generally parallel to said main ceiling portion and positioned generally within said one ceiling-formed housing; and
- (f) air transporting means and diffusing means affixed at the end of said luminaire, said diffusing means sub- 10
15

stantially flush with said light transmitting member and substantially sealingly engaged therewith.
